DESIGN FOR A SHIRT COLLAR

Ida Dietz, Brooklyn, N. Y.

Application June 16, 1936, Serial No. 63,325

Term of patent 7 years

To all whom it may concern:

Be it known that I, Ida Dietz, a citizen of the United States and a resident of Brooklyn, in the county of Kings, in the state of New York, have invented a new, original, and ornamental Design for a Shirt Collar, of which the following is a specification, reference being had to the accompanying drawing, forming a part thereof.

Figure 1 is a side perspective view of the collar when buttoned, and Figure 2 is a front perspective view of the collar when unbuttoned, showing my design.

The characteristic feature of my design resides in the provision on a turned down soft collar of an elongated front section having a relatively large triangular opening between the buttoned tabs as shown, which opening exposes a portion of the shirt front and provides an opening for a necktie, as shown.

I claim:

The ornamental design for a shirt collar, substantially as shown and described.

IDA DIETZ.
